GOGGLE

Anthony J. Desimone, Lyndhurst, and Joseph Mazza, Rutherford, N. J., assignors to Columbia Protektosite Company, Inc., Carlstadt, N. J., a corporation of New Jersey

Application September 30, 1944, Serial No. 556,608

8 Claims. (Cl. 2—14)

This invention relates to goggles and has particular reference to goggles having side shields.

One object of the invention is to provide a goggle and a side shield cooperating therewith in an improved manner to provide a ventilating passage and to so enclose the passage as to fully protect the eyes against any stray light or against flying particles, whereby the goggle may be used by welders or by chippers.

Another object of the invention is the provision of a goggle and side shield having improved means for detachably mounting and reliably positioning the side shield.

Another object of the invention is to furnish a goggle and a light shield having improved inter-connecting means whereby the shield is hooked to the goggle, so that securement is obtained at a plurality of points in a particularly cheap and simple manner to avoid ingress of light at any point.

Another object of the invention is to provide a ventilating goggle having a detachable eye shield having improved means comprising baffles for preventing the ingress of any light.

Another object of the invention is to furnish improved means for connecting a side shield to a goggle having a lens securing ring cooperative with the shield to positively lock the connecting means.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawings, wherein like parts are designated by the same reference characters throughout the several views.

In the drawings:

Figure 1 is a view in side elevation of a goggle and side shield embodying the invention.

Fig. 2 is a sectional view on line 2—2 of Fig. 1.

Fig. 3 is a sectional view on line 3—3 of Fig. 2 with parts omitted.

Fig. 4 is a sectional view on line 4—4 of Fig. 3.

Fig. 5 is an inside plan view of the shield, showing a modification.

Fig. 6 is an edge view thereof.

Fig. 7 is a fragmentary sectional view through a hook.

Fig. 8 is an outside view in elevation of a modi-

fication with parts removed and with a portion of a head band shown in dot-dash lines.

Fig. 9 is a section on line 9—9 of Fig. 8 with the band shown in full lines.

5 The advantages of the invention as here outlined are best realized when all of its features and instrumentalities are combined, but, useful embodiments may be produced involving less than the whole.

10 It will be obvious to those skilled in the art to which the invention appertains, that the same may be incorporated in several different constructions. The accompanying drawings, therefore, are submitted merely as showing a preferred 15 exemplification of the invention.

Referring in detail to the drawings, 10 denotes a goggle embodying the invention. The same includes an eye cup 11 adapted to fit the face of the wearer, and comprising any suitable air inlet

20 openings 12 of angular or Z-shape in a threaded portion on which is screwed a ring 13 for retaining a lens or glass 14. The ring may partially overlie the openings 12 or form a baffle in front of their external ends while air flows into 25 the eye cup 11 and enters the same in a direction against the glass. At its rear outer end, the eye cup may have an opening 15 for attachment of a head band.

Suitable baffled outlet passages for the air in the 30 eye cup are provided by cooperation of the latter with a shield 16 so arranged and constructed that stray light will not enter the eye cup and interfere with the work of a welder. To permit the goggle to be used by a chiper also, the shield

35 is formed with an opening adapted to receive any wire screen button 17 as shown in Figs. 5 and 6, for additional ventilation. When used by a welder, the button 17 may be replaced by an opaque plug 18 to cut off any light through

40 that opening, as shown in Figs. 1 and 2. The elements 17 and 18 are of course identical in diameter and may be secured in place by a frictional fit or by a screw thread.

Marginally formed on the side shield 16 is a lip 19, which is interrupted at 20 to form air outlets, and which merges into a boss 21 as clearly shown in Fig. 5. Confronting each opening 20 is a baffle forming ridge 22, with which cooperate the baffles 23, 24. The baffles 23 extend from the boss 21, while the baffles 24 extend from the marginal wall 19. At each opening 20, the baffles 22, 23, 24 coact with the adjacent portion of the marginal wall 19 to form a double zig-zag path permitting ample flow of air but effectively preventing any stray

50 light from entering the eye cup through the open-

ings 20 even if the eye cup or its shield are made of a white plastic. The baffles make uniform contact with the outer surface of the eye cup, the baffled passages leading to the central region of the shield, which communicates with one or more openings 25 in the wall of the eye cup. If the wire screen buttons 17 are used they communicate with the central region of the shield and thence with the openings 25 of the eye cup, by-passing the baffle passages. The entrance of 10 dust and flying particles is prevented both by the baffles and by the screen buttons.

To conform to the usual shape of the eye cup, the shield 16 is of generally triangular shape, with a base line 26 extending parallel and in close proximity to the lens holding ring 13, and an apical portion lying near the rear of the eye cup. Hence the openings 20 lie at the sides of the triangular shield, and the baffles for one of these openings extend at an angle to the baffles of the other opening. Since the openings 25 lie near the top and bottom of the eye cup, air from all parts of the latter is removed uniformly.

Adjacent to the base line 26, hooks 27 are formed integral with the shield 16, these hooks being spaced apart to engage different portions of the eye cup, for example marginal portions at the ventilating openings 25. It is noted that these hooks project toward the ring 13 so that the latter does not form an obstruction. In other words, to connect the shield to the eye cup, the shield is moved toward the ring 13. The hooks 27 may be further so shaped as to conform to the inner curved surface of the eye cup. In order to prevent lateral movement of the shield along its plane, the hooks 27 engage near lateral edges of the openings 25, and further, the eye cup is provided with a depression which constitutes a seat for the shield. The edges of this depression are clearly shown at 28, 29 in Fig. 2, and at 30 in Fig. 4, but engagement of the hooks 27 is not interfered with, as the shield 16 is adapted to be pivotally moved or swung while the hooks are engaged with the eye cup at the openings 25. It is noted that as these hooks project into the eye cup at the forward end thereof where there is ample room, they form no obstruction for vision nor do they interfere with the smooth seating of the eye cup on the face of the wearer.

Since the hooks 27 are located at least partially rearward of the base line 26 and fairly snugly receive the wall of the eye cup, the shield 16 is thus secured in place. However, it is preferred to render the connection positive as by providing a hole 31 through the boss 21 of the shield, whereby a screw 32 may be inserted into a registering hole in the eye cup, whereby a connection is provided supplemental to that of the hooks 27 and being located at a single, rear point. Thus the triangular shield is affixed in a positive manner adjacent to the three apical portions thereof, so as to prevent even a slight separation of the shield from the eye cup.

In Figs. 8 and 9 is shown a modification comprising an eye cup 11a and light shield 16a generally like those at 11 and 16 except that the screw 32 is eliminated and a positive securing obtained by pressure of the lens holding ring 13 rearward against the forward edge 26a of the shield. At the rear end of the latter is a projection or finger 35 engaged in an opening 36 formed in a raised hollow boss 37, the opening 36 also receiving the head band 38. The finger 35 actually affords a hooked engagement opposite to that of the hooks 27a, and this is possible by providing

that the shield may be slid forwardly to a substantial degree with the hooks 27a engaged and then slid rearwardly to engage the finger 35 in the opening 36, but without disengaging the hooks 27a. In other words, the range of engagement at 27a is greater than that at 35. After such engagement, the ring 13 is tightened to retain the shield in the rearward position and in abutment with the stop portion 37. Since the thickness of the lenses 14 may vary, some resilience is desirable, and hence the shield may be concaved at its forward edge 26a to contact the ring 13 at spaced points 39, whereby a degree of spring is obtained. This is sufficient to accommodate lenses of different thicknesses and to reliably hold the shield. Thus it is seen that a practical positive connection is obtained without the use of any screw, and this is important especially with most plastics which have little resilience and therefore do not permit the use of spring catches and the like.

We claim:

1. A goggle having an eye cup member having a ventilating opening, a concave light shield member overlying the opening and cooperating with the eye cup member to provide a ventilating passage through said opening, the shield member being of generally triangular shape and having one end at the rear of the eye cup member, a first means detachably interconnecting the members at the front end of the same, including spaced hooks integral with one of the members, the other member having portions under which the hooks are engageable for interconnecting the members, and a second means detachably interconnecting the members at the rear thereof, the first and second means cooperating with each other so that the hooks are disengageable only upon first disengaging the second means, and a series of baffles 30 in the shield member integral therewith and engaging the wall of the eye cup member when the members are interconnected.

2. A goggle having an eye cup member, a light shield member cooperating with the eye cup member to provide a light shielded ventilating passage, a hook means integral with one of the members, the other member having an opening portion receiving the hook means, and supplemental means spaced from the hook means for interconnecting the members at a point to thus retain the shield member from pivotal movement about the hook means, the latter and its opening portion cooperating with each other to prevent lateral shifting of the shield in its plane, the opening of said portion being covered by the shield member, said light shield member having a series of baffles connected thereto and being concave to receive the baffles, the latter engaging the wall of the eye cup member when the members are interconnected to furnish a baffled ventilating passage.

3. A goggle according to claim 2 wherein the supplemental means comprises a projection on the shield member, the eye cup member having an opening portion remote from the ventilating passage, the projection and the opening portion having hooked engagement with each other, the eye cup member having a threaded lens clamping ring, said ring abutting the shield member to move the same so that the projection is engaged in its opening portion, the members being thus movable relatively to each other without disengaging the hook means, the shield member being removable by at least partially loosening the ring

and shifting the shield member to disengage the projection to permit release of the hook means.

4. A goggle including an eye cup member, a light shield member forming a ventilating passage therewith, the eye cup member having a lens holding ring, means whereby the members are slidably interconnected, said means being biased for positive interconnection in a direction away from the ring, the latter and the shield member cooperating with each other so that the ring moves the shield member to render the connecting means positive.

5. A goggle having an eye cup member having a temporal wall provided with a ventilating opening, a plate overlying said wall and extending beyond said opening, said plate being concave and having a marginal rim, said plate having a series of integral baffles within the concavity, said baffles engaging the said eye cup wall to provide a baffled passage to said opening, said rim having a recess forming a vent opening communicating with the baffled passage, and means interconnecting the plate with the said wall of the eye cup member.

6. A goggle having an eye cup member having a temporal wall having a ventilating opening, a plate overlying said wall and said opening, said plate being concave and having a marginal rim, a series of baffles connected to the plate and located in the concavity of the plate, said rim and baffles

contacting said wall to provide a baffled passage leading to said opening, said baffles being located lateral to the opening, the plate having a vent opening spaced laterally of the first mentioned opening and communicating with the baffled passage, and means detachably connecting the plate to said wall adjacent to the rim.

7. A goggle according to claim 6 wherein the connecting means includes a hook integral with the plate located within the rim and engaging said wall through said ventilating opening.

8. A goggle having an eye cup member, a light shield member cooperating therewith to provide a ventilating passage, the shield member having an opening leading to said passage and having baffles for said passage, the shield member having a hook and the other member having an opening in which the hook is engaged, the shield member overlying the opening in the eye cup member, and means interconnecting the members supplemental to the hook, said eye shield member being provided with a second opening at a point in said passage spaced from the baffles whereby the latter can be by-passed, the second opening being adapted to selectively receive a closure plug or a screen element whereby the goggle is adapted for use by a welder or a chipper.
